UNITED STATES PATENT OFFICE.

WAYNE F. PALMER, OF WASHINGTON, DISTRICT OF COLUMBIA.

SUBMARINE MINE.

Application filed May 13, 1920. Serial No. 381,286.

To all whom it may concern:

Be it known that I, WAYNE F. PALMER, a citizen of the United States, residing at Washington, District of Columbia, have invented new and useful Improvements in Submarine Mines, of which the following is a specification.

This invention relates to submarine mines, and more particularly to submarine mines 10 of the single needle magnetic ground type.

One of the objects of the present invention is to provide an improved magnetic influence mine firing device of simple and practical construction.

Another object of this invention is to provide a submarine mine firing device which will be reliable and efficient in use and operation.

A further object is to provide a mine 20 firing device of the above general character, which will be safe to handle, and which will not assume an armed condition until a predetermined time after the same is launched.

A further object is to provide a mine 25 firing device of the above general character, or i. e., one having an increased radius of action, which may be inexpensively manufactured and assembled.

A further object is to provide a mine 30 firing device of the above general character which is, in itself, proof against countermining or other external disturbances.

A further object is to provide a mine 35 firing device of the above general character, into which has been incorporated a safety switch, which necessary adjunct has previously formed a separate device.

A further object is to provide a mine 40 firing device of the above general character which is not detrimentally affected by the presence of iron junk in the vicinity of the mine, or iron impurities in the working parts of the mechanism itself.

Other objects will in part be obvious, and 45 in part hereinafter pointed out.

In order that a clearer conception of the present invention may be had, several sheets of drawings are annexed, forming part of this application, and in which corresponding parts are indicated by similar reference characters.

In these drawings, Figure 1 is a sectional elevational view of such parts of a submarine mine as are necessary to understand 50 the invention.

Figure 2 is a vertical sectional elevational view of a portion of the firing mechanism before it assumes an armed condition.

Figure 3 is a vertical sectional elevational view of a portion of the firing mechanism 60 after it has assumed an armed condition.

Figure 4 is a plan view of a locking device, to more fully understand the invention.

Figure 5 is a plan view of the contacts, in order to more fully understand the invention.

Submarine mines now in general use comprise a casing adapted to contain a relatively large amount of explosive, which explosive is fired by means of a detonator 70 actuated in any one of several well-known manners. The present type of mine which is more specifically known as a single magnetic needle type is adapted to fire the detonator by means of an electric battery 75 when, on the approach of a metal ship, the magnetic needle has swung through a predetermined arc to engage a fixed contact point.

As the general arrangement and operation 80 of mines of this character are now becoming more or less well-known, it is believed to be unnecessary to go into a detailed statement thereof. It is sufficient to state that a magnetic needle, including one contact will 85 turn about its pivot point on the approach of an iron or steel ship to bring one of its ends into engagement with a second contact point thereby establishing a circuit through the two contacts and a battery to 90 fire a detonator.

In this manner the mine is given a relatively large radius of action.

Referring now to the accompanying drawings, and more particularly to Figure 95 1, 10 denotes a portion of the mine casing provided with an opening in which is seated a firing mechanism, the more active part of which is contained within a pot or chamber 11 mounted within the mine casing. The opening in which this casing is set is provided with a flange 12 and gasket 13 supporting the casing while it is held tight thereagainst by means of a ring 14 of bayonet joint construction provided with set screws 15, whereby when the parts are assembled, as shown in Figure 1, the casing 11 is urged downward into water-tight position. The upper part of the casing 11 is provided with a cover 16 perforated at 110

17 and threadedly secured at 18 to the casing 11. Between the casing and cover is a flexible diaphragm 20 which may be subjected to hydrostatic pressure as indicated by the arrows when the mine is launched. Centrally secured to the plate or cover 16, is a pin 21, provided with a shoulder 21' having mounted thereon a cup-shaped member 27, rigidly secured to the shoulder 21' by a wing-nut 27'. The pin 21 carries a member 25' provided with a stem 26', having screw threaded engagement at 28' with an annular disc-like member 22. The member 22 is provided with a cup shaped portion 22' which fits over the cup shaped member 27. The cup shaped member 27, and the cup shaped portion 22' are provided with openings 28 which in the position shown are adapted to register. The member 22 is normally held in the position shown against the action of an expansion spring 23, by means of a transverse pin 24 carried by the stem 21 extending through a slotted portion 29' in the stem 26'. The pin 24 co-acts with the underside of a washer 25 and a soluble washer 26, the member 25' and the cup shaped member 27. On launching the mine, water passes inward through openings 28 and dissolves the soluble washer 26, thus permitting the member 25' and plate 22 to move bodily downward to bring a rubber gasket 30 into engagement with the cover 16. Thus is prevented consequent variation of the hydrostatic pressure on the diaphragm 20 which might be caused by either natural conditions due to the rise or fall of tide or countermine operations.

It is to be understood that the interior of the casing 11 is filled with any suitable non-corrosive, non-freezing insulating fluid, for example, kerosene, adapted to cushion the movement of the pot which contains the contact mechanism, and which is hereinafter described. After the mine has been launched the diaphragm 20 is depressed by the hydrostatic pressure. This pressure is transmitted to the contact mechanism for a sufficient length of time to accomplish the desired result, after which the diaphragm is sealed against further hydrostatic and countermine action.

Mounted in suitable trunnions 31 and 32, one of which is insulated as shown at the right of Figure 1, is a gimbal ring 33, adapted to support in trunnion 34 a second casing 35, shown in detail in Figure 2, which carries the contact mechanism. This casing 35 is cylindrical in shape for ease in construction and assembly. It is provided with extending arms 36 and 37 which are diametrically opposite, and one of which is engaged by a trunnion 38, electrically connected at 40 with one terminal of the battery, as will hereinafter be ex-

plained, and has its opposite end seated in insulating bearing 41. The other trunnion 42 is not insulated from the arm 37 which forms an integral part of the casing. It will likewise be seen that the trunnion 38 is insulated from the gimbal ring 33 by means of bearing 43.

Within the casing 35 there is pivotally supported a magnetic needle 44 which is adapted to co-act with bifurcated fixed contact 45. It will thus be seen that when the mine is in armed condition current will pass from a battery 46 through wire 47 and trunnion 32 to gimbal ring 33, thence in through trunnion 42, Figure 2, to the casing 35 through contacts 45, through the contact piece 48 of the needle 44 (when the mine is in firing condition), thence out through the pivot point 50 and wire 51 to rotatable contact 52 on trunnion 38, and out through the wire 40 to insulated trunnions 31 and wire 53 to detonator 54, thus completing a circuit.

Taking up the construction of the firing mechanism within casing 35 it will be seen that the lower end is open and provided with a close-fitting member 60 of piston-like construction. Just above this member is a perforated insulating disc 62 through which rods 63 pass freely as shown. The upper ends of these rods 63 support a second insulating annular member 64, the center of which is the pivot point of pivot 50, which is also the center of spherical member 65 which carries the bifurcated contact members 45. Before arming, member 65 can revolve in any plane around the pivot point without coming into contact with member 64. In the process of arming member 64 will lift piece 65 from its support by gripping it along some circumference regardless of its tilt. This permits of the least possible disturbance to piece 65 and thereby makes improbable premature firing, due to the contact of members 45 and 48. This member 65 is buoyed by cork portion 66 which is so chosen as to give member 65 just enough negative buoyancy to guarantee its hollow squared center resting on the squared top of insulating member 70. Secured to the top of piece 65 is a light, metallic shell 77, so constructed as to make electrical contact with the face 72 of member 73 when the mine has assumed an armed condition. Insulating member 70 is threadedly secured to the magnet carrying member 74 on which rests magnet 44 and contact 48. This conical member 74 rests on jeweled pivot bearing 75 which in turn rests on pivot 50.

Previous to the arming of the mine the casing 35 is completely filled with oil, while expansion chamber 67' contains only approximately $\frac{1}{2}$ " of oil, which amount is considered sufficient to keep casing 35 completely filled, even during extreme cold. The

hole 71 in member 73 is the communicating passage between casing 35 and expansion chamber 67'. It is of very small diameter, approximately $\frac{1}{2}$ ".

5 The purpose of the fluid throughout the mechanism is to dampen out all sudden or oscillatory motion of the magnetic system and to reduce the effect of any shock from without in causing injury or violent motions 10 of the delicate parts within, and thus to prevent accidental contact between the members 45 and 48. The fluid also serves the purpose of acting upon suitable counterbalancing floats 66, 67 and 76, thereby to reduce to a 15 minimum the pressure and friction due to the pressure of the cone and parts carried thereby upon the pivot point 50. The floats have large surfaces, and the friction between the surfaces and the fluid aids 20 in dampening the movement of the magnet.

In accordance with the present invention, the buoyance provided by the float members is increased until each unit of the magnetic system is as near the specific gravity of the 25 immersion fluid as restricting conditions permit, that is to say, the specific gravity of each of these units is but slightly greater than the specific gravity of the immersion fluid. The center of buoyance of each of the 30 units of the system is near the center of gravity of the respective units, and the center of buoyance of the magnetic system taken as a whole, is as near the center of gravity of the entire system as will insure the system 35 remaining in an upright position. The center of buoyance of the system is preferably immediately above the center of gravity of the system. Since enough flotation is added to the buoyancy of each unit of the system 40 to render its specific gravity only slightly greater than the specific gravity of the immersion fluid, the fluid and the magnetic system will move substantially in unison; that is to say, if the casing 11 together with the immersion fluid therein, is subjected to any rectilinear accelerated movement, the system of magnets will not tend to lag behind nor move forward more rapidly than the immersion fluid itself. This provision is especially effective in protecting the magnet system in 45 whole and in part from being disturbed by sudden shocks or impulsive accelerations imposed upon the shell 11 and casing 35 from without. By constructing the system so that the center of buoyance is slightly above, but as near to the center of gravity as will insure the members remaining in an upright position, the position of the meta-centers is such that the system is always stable.

50 A further method of eliminating the possibility of shocks being translated to the magnet 44 is found in the arrangement of the gimbal rings, trunnions and pivot point. It will be noted that the pivot point 50 is the 55 center of the entire mechanism. In motions

of the mine, other than the translation of the mine as a whole, the only possible movement of the magnet 44 is about the pivot point 50, which point is located at the point of zero motion.

When the mine is submerged, hydrostatic pressure will immediately act on diaphragm 20. This pressure will be communicated by the dampening fluid in casing 11 to piston 60, which will be forced upward. Its motion will be retarded by the liquid contained in casing 35, which must make its way through communicating hole 71 into the expansion chamber 67'. Approximately thirty minutes will be required for piston 60 to 70 complete its travel. During this operation member 65 is lifted from insulating member 70 and is carried upward by insulating ring 64. The spherical cork 66 and cap 77 are forced into the receiving surface 72 of plate 73, which concave surface is of the same radius as members 65, 66, and 77. Locks 78 (detailed in Figure 4), and groove 79 of rods 63 hold the elevated parts in extreme elevated position.

During the operation of arming, previous to the engagement of the insulating ring 64 and member 65, the following parts had been free to gyrate as one member about pivot 50: cone 80, which normally carries magnet 44, buoyant members 76 and 67, contact 48 and insulating member 70, superimposed on which temporarily is member 65 with its cork 66, cap 77, and bifurcated contact 45, so placed as to straddle evenly contact 48. Soon after the mine settles down on the sea bottom, magnet 44 will, with the above listed parts, revolve on pivot 50 until it places its magnetic axis along the magnetic meridian. When member 65 is lifted 90 free from its insulated support 70, and is jammed into its receiving cup 72, contact 45 will still straddle contacts 48 evenly, and remain in that position until the axis of magnet 44 is rotated from its position along 95 the magnetic meridian by the approach of any relatively large mass of iron.

Returning now to the larger casing 11, it is noted that the fluid therein is still subjected to the external hydrostatic pressure, which, over a long period, is undesirable. After a predetermined time, soluble washer 26 gives way, and spring 23 forces member 22 and its gasket 30 down on plate 16, and the contents of pot 11 are now protected 100 against all disturbing forces excepting magnetic influences which are used in closing the firing circuit.

It is believed from the above that the construction, the method of use, and the operation will be clear to those skilled in the art and a further statement thereof is doubtless unnecessary.

Without further analysis, the foregoing will so fully reveal the gist of this inven- 125

tion that others can by applying current knowledge readily adapt it for various applications without omitting certain features that, from the standpoint of the prior art, 5 fairly constitute essential characteristics of the generic or specific aspects of this invention, and, therefore, such adaptations should and are intended to be comprehended within the meaning and range of equivalency of 0 the following claims.

What I claim is:—

1. In a submarine mine, in combination, a main casing having a diaphragm subjected to hydraulic pressure on launching 5 and means for cutting out the action of hydraulic pressure on said diaphragm after the mine has been submerged a predetermined time.

2. In a submarine mine, in combination, 0 a main casing having a diaphragm subjected to hydraulic pressure on launching and means for cutting out the action of hydraulic pressure on said diaphragm after the mine has been submerged a predetermined 5 time, said means including a closing member, means for moving said closing member and soluble means to permit movement of said closing member.

3. In a submarine mine, in combination, 0 a casing adapted to contain fire control means, a diaphragm closing said casing, said casing being filled with a fluid adapted to transmit hydrostatic pressure to the fire control means when the mine is launched and 5 means for preventing hydrostatic action on said diaphragm after the mine has been submerged a predetermined time.

4. In a submarine mine, in combination, fire control means therefor comprising a main casing and a secondary casing mounted in gimbal rings therein, said casing being filled with a fluid, a diaphragm exposed to hydrostatic pressure on launching the mine for transmitting pressure through 5 said fluid to arm the fire control mechanism after a predetermined time.

5. In a submarine mine, in combination, fire control means therefor comprising a main casing and a secondary casing mounted in gimbal rings therein, said casing being filled with a fluid, a diaphragm exposed to hydrostatic pressure on launching the mine for transmitting pressure through said fluid to arm the fire control mechanism after a predetermined time, and means for locking 115 said mine in armed position.

6. In a submarine mine, in combination, fire control means therefor comprising a main casing and a secondary casing mounted in gimbal rings therein, said casing being filled with a fluid, a diaphragm exposed to hydrostatic pressure on launching the mine for transmitting pressure through said fluid to arm the fire control mechanism after a predetermined time, and means for cutting 130

off the variations in hydrostatic pressure after a predetermined time.

7. In a submarine mine, in combination, an auxiliary casing, fire control mechanism therein comprising a pair of contacts one of 70 which is mounted on a magnetic needle and means for keeping said contacts in relatively locked position for a predetermined time after the mine is launched and means for thereafter unlocking said contacts to permit 75 relative movement thereof.

8. In a submarine mine, in combination, an auxiliary casing, fire control mechanism therein comprising a pair of contacts one of 80 which is mounted on a magnetic needle and means for keeping said contacts in relatively locked position for a predetermined time after the mine is launched, means for thereafter unlocking said contacts to permit relative movement thereof, said second means 85 including a piston-like member adapted to separate said contacts in the direction of the axis of the magnetic needle.

9. In a submarine mine, in combination, a secondary casing adapted to contain fire 90 control mechanism including a pair of contacts adapted to be electrically connected with the detonator, said contacts being normally locked against relative movement until after the mine has been launched a predetermined time and means for conveying hydrostatic pressure to said secondary casing 95 to cause a relative separation of said contacts in the direction of the axis of one of them and means for cutting off the effect of hydrostatic pressure upon said contacts after the mine has been launched a predetermined time.

10. In a submarine mine, in combination, a secondary casing adapted to contain fire 105 control mechanism including a pair of contacts adapted to be electrically connected with the detonator, said contacts being normally locked against relative movement until after the mine has been launched a predetermined time, means for conveying hydrostatic pressure to said secondary casing to cause a relative movement of said contacts in the direction of the axis of one of them and means for locking said contacts in their 110 moved position.

11. In a submarine mine, in combination, an auxiliary casing having a movable bottom adapted to be actuated by hydrostatic pressure, a magnetic needle pivotally mounted in said casing and provided with contacts, a second contact member normally resting on said first mentioned contact and held in fixed relative position thereto until after the mine has been launched a predetermined time, said contacts being normally electrically separated and forming part of an electric circuit and means connected with said movable bottom of the auxiliary casing whereby said second mentioned contact is 125 130

5 moved axially with respect to the pivot point of the magnetic needle whereby consequent material movements of the magnetic needle will cause a closing of the circuit.

10 12. In a submarine mine, in combination, an auxiliary casing having a movable bottom adapted to be actuated by hydrostatic pressure, a magnetic needle pivotally mounted in said casing and provided with contacts, a second contact member normally resting on said first mentioned contact and held in fixed relative position thereto until after the mine has been launched a predetermined time, said contact being normally 15 electrically separated and forming part of an electric circuit, means connected with said movable bottom of the auxiliary casing whereby said second mentioned contact is moved axially with respect to the pivot point 20 of the magnetic needle whereby consequent material movements of the magnetic needle will cause a closing of the circuit and means preventing a return of said contacts to unarmed position.

13. In a submarine mine, in combination, 25 an auxiliary casing having a movable bottom adapted to be actuated by hydrostatic pressure, a magnetic needle pivotally mounted in said casing and provided with contacts, a second contact member normally resting 30 on said first mentioned contact and held in fixed relative position thereto until after the mine has been launched a predetermined time, said contact being normally electrically separated and forming part of an electric 35 circuit, means connected with said movable bottom of the auxiliary casing whereby said second mentioned contact is moved axially with respect to the pivot point of the magnetic needle whereby consequent material 40 movements of the magnetic needle will cause a closing of the circuit and means for cutting out the action of variations in hydrostatic pressure upon the movable bottom of said auxiliary casing. 45

Signed at Washington, District of Columbia, this 9th day of December, 1919.

W. F. PALMER.
